UNITED STATES PATENT OFFICE.

ALFRED L. LOOMIS, OF TUXEDO PARK, NEW YORK.

CHRONOGRAPH.

1,409,304.

Specification of Letters Patent. Patented Mar. 14, 1922.

Application filed August 16, 1919. Serial No. 317,986.

(FILED UNDER THE ACT OF MARCH 3, 1883, 22 STAT. L., 625.)

To all whom it may concern:

Be it known that I, ALFRED L. LOOMIS, a citizen of the United States, and a resident of Tuxedo Park, Orange County, and State of New York, have invented an Improvement 5 in Chronographs, of which the following is a specification.

The invention described herein may be used by the Government or any of its officers or employees in prosecution of work for 10 the Government, or by any other person in the United States, without payment of any royalty thereon.

This invention relates to chronographs or 15 other recording instruments used to graphically record the occurrence of events whether taking place at fixed or variable intervals, and deals more specifically with the carrier of, or support for the recording medium.

20 To that end, an object of the invention is to improve the rotating drum usually employed in most recording instruments, by the provision of means of construction, which shall increase the accuracy, convenience 25 and speed of operating such instruments.

The invention is particularly applicable to instruments in which the record surface moves at a high rate of speed in order that 30 short time intervals, for instance, may be indicated on the surface and measurable with great accuracy. Such conditions exist in instruments used to graphically record the exceeding small time intervals measured in 35 determining the velocity of projectiles and shell fragments, or the rate of propagation of a detonation wave.

Another object is to so construct the carrier for the record medium, that the latter 40 may be applied to and removed from the rotating support without interfering with its rotation and without necessitating the dismounting or removal of any part of the apparatus.

45 A further object of the invention is the construction of a record support in which centrifugal force is used to maintain the record medium or strip in place, thus dispensing with any fastening means, which 50 might tend to unbalance the carrier or vary the true length of the record surface.

A preferred embodiment of the invention

is disclosed in the accompanying drawings, in which—

Fig. 1 is a view showing the drum and 55 record strip in cross section, and a means for rotating the drum, and

Fig. 2 is a perspective view of the carrier or drum.

The record carrier is shown in the form 60 of a shallow, cup-shaped cylinder or drum 1 of cast aluminum or other material mounted with its axis vertical. The central spindle of the drum is connected to and driven at a high rate of speed by any suitable means, 65 in the illustration, a small electric motor 2, supported on a bracket arm 80 carrying a pivot rod 82 on which is mounted an insulation block 81 in which block the spark points 43, 43' and 43'' are secured. The inner 70 periphery of the drum carries the record surface 3, shown as a narrow strip, or ribbon, of prepared paper or other suitable substance held there solely by the centrifugal force developed by the rotation of the 75 carrier.

The spark points and the drum 1 are in electrical connection with respective screens, not shown, so that, as a projectile 80 passes through each screen circuit is made to cause a spark to pass between the point and the drum, piercing the ribbon or strip 3. Knowing the speed of the drum and having the distances between the spark punctures of the ribbon, the speed of the projectile 85 can be determined.

Below the drum is conventionally shown a common form of governor 5 mounted on the shaft 4 to maintain the rate of speed of the motor constant, and as this invention is 90 not concerned with it no further description thereof is necessary.

The drum is balanced and acts as a flywheel for the motor and by the use of centrifugal force all gluing or pasting of 95 the record strip or surface is eliminated. The errors liable to such procedure, as the pulling away of the strip from the carrier, if secured to the outside of the drum, due to its rotation, or the irregularities of the 100 surface, due to the varying thickness of the adhesive layer employed, are also thus eliminated. The balance of the drum is also maintained, as could not be the result were

it necessary to employ clips or the like to maintain the strip on the carrier.

The rate of speed of the drum, being constant and determined, and the circumference or rather inner periphery being accurately known, the time interval between the occurrence of any two events is of simple determination. Marks being obtained on the record strip in any well known manner, as by any means of styluses or electrical sparks, the linear measurement of the distance between such marks is all that is necessary.

The record strip, after marks have been made, may be removed without stopping the rotation of the carrier as but a very slight force of the fingers is required to lift the

strip out. The new strip may similarly be fed into the drum without stopping its rotation. The strip need not be exactly of the same length as the inner periphery of the drum.

What is claimed as new and desired to secure by Letters Patent is:

In a chronograph, a source of power, a shaft rotated by said power, a shallow cup-shaped drum mounted on the shaft and acting as a fly wheel therefor, the inner periphery of the drum providing a surface against which a strap of thin record material is held, when the shaft is rotated, by the action of centrifugal force alone.

ALFRED L. LOOMIS.
